UNITED STATES PATENT OFFICE.

CHARLES STAMPER AND JAMES D. STAMPER, OF CINCINNATI, OHIO.

POLISHING-MACHINE FOR MARBLE AND ANALOGOUS MATERIALS.

No. 870,321.

Specification of Letters Patent.

Patented Nov. 5, 1907.

Application filed September 21, 1906. Serial No. 335,657.

To all whom it may concern:

Be it known that we, CHARLES STAMPER and JAMES D. STAMPER, citizens of the United States, and residents of the city of Cincinnati, in the county of Hamilton and State of Ohio, have invented certain new and useful Improvements in Grit and Polishing Machines for Marble and other Analogous Materials, of which the following is a specification.

- The mechanism embodying our invention is applicable not only for the grinding and polishing of marble, but for the grinding and polishing of any other materials capable of such treatment, when it becomes desirable to subject them to either or both of such operations, namely: of grinding or polishing.
- 15 The several features of our invention and the various advantages resulting from their use conjointly or otherwise will be apparent from the following description and claims.

We will now proceed to describe our invention in detail.

In the accompanying drawings, making a part of this application, and in which similar letters of reference indicate corresponding parts,—Figure 1 is a perspective view of a machine embodying our invention, 25 and placed upon a slab of marble supported on a table. Fig. 2 is a view partly in section and partly in elevation of the machine shown in Fig. 1. The section is a vertical one taken in the plane of the dotted line 2, 2, of Fig. 1. In this view, the ball and its lugs and the upward extension of this ball are shown in elevation. The pipe above the extension of the ball which is shown in Fig. 1, is omitted from this figure. Fig. 3 is a top view of the socket (the cover thereof having been removed) and showing the ball with lugs located 30 therein, the upper end of the portion which is integral with the ball being shown in section, the section being a horizontal one taken in the plane of the dotted line y, y, of Fig. 2. Fig. 4 represents a vertical central section of one part of the machine. This section is taken 35 in the plane of the dotted line 4, 4, of Fig. 6. The section is taken beginning above the horizontal plane of the dotted line x, x, of Fig. 2, and extending down to the bottom of the machine. Fig. 5 represents a vertical central section of another part of the machine. This section is 40 taken in the plane of the dotted line 5, 5, of Fig. 6. The section is taken beginning above the horizontal plane of the dotted line x, x, of Fig. 2, and extending down to the bottom of the machine. Fig. 6 is a plan view of some of the grit holders, adjacent to one another, when 45 the elevating screw sleeve and the annular securing plate have been removed. Fig. 7 is a bottom view of some of the grit holders, showing certain of their relations to each other. Fig. 8 is a perspective view of the under side of that discal series of grit holders whose 50 central connecting ring is uppermost. Fig. 9 is a perspective view of the top side of that discal series of grit

holders whose central connecting ring is undermost. The discal series shown in these two Figs. 8 and 9 are so placed as to the better enable the reader to understand how the central ring in Fig. 8 fits down over the 60 cylindrical ring in Fig. 9, with the understanding that an intermediate screw threaded cylinder fits over this last named cylindrical ring. Fig. 10 is a perspective view of this intermediate screw ring.

One of the objects of our invention is to provide convenient means whereby, in the same machine, polishing grits of different degrees of fineness for successive operations upon the stone to be ground and polished, are contained in the one machine and are capable of adjustment relatively to each other and to the stone to 65 be operated upon, and of application successively to the stone to be ground and polished.

Other objects will be apparent in connection with the specification of the features of our invention.

The polishing disk is composed of a series of grits 75 held in holders projecting radially from the central portion of the machine. The means for rotating the disk is adjustably connected to the disk by a joint which is substantially as follows. To this end, we interpose between the polishing disk and the means 80 whereby a rotary movement is imparted to it, a joint which is substantially as follows. C indicates a socket and B the ball received therein. This ball has preferably an extension B². The preferred means for imparting a rotatory movement to this ball consists of the 85 shaft A extending beyond the extension as shown. For perfection and ease of construction, this shaft should be first made separately from the ball and inserted therein.

For the retention of the ball B within the socket C, 90 we provide a cap D, and means for securing it to the socket. In the present illustrative instance, the cap has an interior screw thread D², adapted to engage the male screw thread C² of the socket C.

The preferred means for rotating the cap, so as to 95 screw it down and upon the socket, or vice versa, are the sides(faces) D³, which latter constitute projections which a wrench can engage. To enable the ball B, when rotated, to impart its rotation to the socket C, and thence to the polishing disk F, we provide grooves 100 C⁵ in the socket C, and provide the ball with lugs (projections) B³. Each lug B³ fits into and can travel in its groove C⁵. The grooves are in planes parallel with the plane of the axis of the socket C and disk F.

According to one feature of our invention, the four 105 detents, or lugs B³ are located on the ball, in a plane passing through a diameter of the ball proper, as shown. Thus the part C and consequently the grinding disk have free opportunity to oscillate on these lugs as pivots.

110 We have shown four lugs B³ projecting from the ball. These, even if the grooves in which they worked fitted

them closely, would give the socket great capacity for movement in various directions for enabling the grinding disk or plate to be flat against the article K. These grooves C³ are wider than the lugs B³, and afford the latter considerable play therein. In consequence, the capability of the ball and socket joint, as we thus construct it, allows the grinding disk to lie flat upon the table under all the requirements to which such a machine is subject.

10 The socket C is duly connected to the polishing disk.

As it is our purpose to use the foregoing feature of automatic adjustment, rendered possible by the ball and socket construction hereinbefore described, with a very advantageous construction of the disk for enabling 15 grits of different degrees of fineness to be carried and successively applied to the stone or like article in the operation of polishing it, we will now describe such construction of the disk and then mention the preferred manner of connecting the socket to this constructed 20 device.

There are two series of grit holders each of which when separated from the other will be seen to constitute a polishing disk of itself. Thus in Fig. 8, one series of the grit holders in the compound disk F constitutes 25 a disk E, and in Fig. 9, the other series of the grit holders in the compound disk F constitutes a disk G.

Our improved construction enables the disk E with its grit holders to be used in connection with the disk G and its grit holders. Both of the disks E and G are 30 rotated by one and the same rotatory mechanism.

The grit holders of the disk E have grits of a given degree of fineness, and the grit holders of the disk G have grits of a degree of fineness different from those of the disk E. The disk E with its grits can be elevated 35 while the disk G with its grits are depressed, and vice versa.

The grit holders of each disk E and G are preferably hollow frames, into which grits of preferably the same shape as the interior space of each grit holder are 40 respectively put. Any proper means for holding each grit in position in its holder may be employed. A convenient means is the set screw Z engaging a female screw in the holder and capable of being advanced into the holder and against the grit, to hold the latter 45 stationary in the holder, and capable of being retracted, and thereby allowing the grit to be withdrawn, and a new one substituted therefor.

In order to utilize the space allowed by this construction, the grit holders of each of the disks E and G 50 are made of the shape shown, and are larger at their outer edge than at their inner one.

The grit holders of disk E are placed at intervals, so as to allow spaces V between them in which the grit holders of disk G can be respectively present and the 55 grit holders of disk G are placed at intervals so as to allow spaces W between them in which the grit holders of disk E can be respectively present.

We indicate each of the grit holders of the disk E by the character E². We indicate each of the grit holders 60 of the disk G by the character G².

The rear or inside end of each of the grit holders E² of the disk E extends upward and is connected to a ring E³. The rear or inside end of each of the grit holders G² of the disk G is connected on a level to the 65 cylindrical ring G³. This latter ring G³ extends up

within the ring E³. An intermediate cylindrical ring J is between the ring E³ of the grit holders E² and the cylindrical ring G³. This intermediate ring J has an external (male) screw thread J². The ring E³ of the grit holders E² has a screw thread E⁴ formed on its interior surface. The screw thread J² of the intermediate ring J engages the screw thread E⁴ of the ring E³ of the grit holders E². The cylindrical ring G³ of the grit holders G² extends up inside of this intermediate ring J. The cylindrical ring G³ and its grit holders G² are 70 supported by the intermediate ring J. A preferred means for so doing consists of the flat ring Q. The latter rests upon the top of the intermediate cylindrical ring J and is secured to the top of the ring G³, preferably by screws Q², Q², Q², Q², as indicated. 80 But the flat ring Q is not fastened to the top of the intermediate ring J. On the contrary, this ring J is free to rotate under this ring Q. In order to enable the intermediate ring J to be rotated, we provide suitable means, preferably a ring S, fitted onto the periphery 85 of ring J and secured thereto by set screws S². In the periphery of this actuating ring S are recesses S³, wherein in the point of a wrench suitable for such work can be introduced, and the ring S by means of said wrench be rotated.

The interior of the ring G³ is provided with a screw thread G⁴ adapted to engage a screw thread C⁴ on the lower extension C³ of the socket C. The screw connection G⁴ and C⁴ is a preferred mode of connecting the rotatory socket C with the compound disk F. 95 Thus connected, the rotation of the main shaft A, through the intermediate connection of the ball and socket as described, rotates the disk G and the disk E.

The central opening provided in connection with the construction aforementioned is as follows:—The 100 shaft A is tubular and is therefore provided with a passage M. In the ball B is an orifice M². In the socket C is a passage M³, and in the ring G³ is a passage M⁴ extending down through this ring. These passages M, M², M³, M⁴ at all times so connect as to enable water 105 passing down through the pipe A to reach the article K which is being operated upon. The water flowing out from the bottom of passage M³ does lubricate, so to speak, the contact between the article K and the grits at work on it, and also serves to carry away the fine 110 dust or pulverized matter which the grits make in grinding the article K.

The operation of the disk E and the disk G relatively 115 to the stone or other article to be ground and polished is as follows: It makes no difference in the final result whether those coarser grits which are adapted for the first step in the operation of grinding and polishing be placed in the grit holders E² or in the grit holders G². In either event, the finer grits are put in the other grit holders, and where both sets of grits are successively 120 used, the finer grits will obviously be ordinarily used last. For illustration, let us place the coarser grits in the grit holders E², and place the finer grits in the grit holders G². The screw actuating ring S is now rotated, and thus the intermediate ring J is turned in 125 the proper direction, and by means of the screw thread E⁴ in ring E³, and the screw thread J² of the intermediate ring J, the ring E³ and its grit holders E² are lowered and brought into contact with the stone or other article to be polished, and the ring G³ with its 130

- grit holders G² is elevated above and out of touch with the stone, etc. to be operated on. The machine is now set in motion, and the shaft A rotates and rotates the ball and socket and the latter rotates the ring G³ 5 with its grit holders G², and the latter rotates the grit holders E² and their ring E³. The intermediate ring J will rotate with the rings E³ and G³. Insomuch as the coarser grits in the holders E² are in contact with the article to be ground, the latter will be ground off 10 rapidly, and thus the object in using the coarser grits is fully accomplished. When the grinding off of the material of the article has proceeded sufficiently far, the machine is stopped. The intermediate ring J is now turned in a direction the contrary to that in which 15 it was turned when the coarse grits in the holders E² were put into contact with the article. As a result of this reverse rotation, the ring E³ is raised and its grit holders E² are raised out of contact with the article which has been ground, and the ring G³ is lowered, and 20 the grit holders G² fast to this ring G³ are brought down and the grits in these last named holders are brought into contact with the article which has been ground by the coarse grits. The machine is again started, and the grit holders are revolved. The fine grits grind off 25 the article and give it a smoother and more polished surface. When this second operation has been finished, the machine is stopped and the article operated on is withdrawn. The foregoing operations are repeated upon a new article to be ground and polished. 30 Before beginning to grind the new article, the intermediate screw ring J is again turned in a direction contrary to that in which it was last rotated, and the coarse grits in the holders E² are lowered down upon the article to be ground, and the fine grits in holders 35 G² are raised away up out of contact with said article. Where only one set of the grits is employed, that set is lowered onto the article to be operated upon, and the other set moved up out of the way. In explanation of the fact that the stem of the socket 40 being connected with ring G³ only, turns not only the grit holders of that ring, but also turns the ring E³ and the grit holders of the latter, it should be noted that the grit holders E² of the ring E³ lie respectively between the respective grit holders G² of the ring G³ and 45 in juxtaposition therewith. Hence the revolution of the grit holders G² compels the revolution of the grit holders E². The separation vertically of the two sets of grit holders is never so much as to have the holders E² of the 50 disk E out of contact with the holders G² of disk G. Among the various advantages resulting from the use of our invention are the following: The grit holders for the two kinds of grinding and polishing are always on hand and can be used at any time, and are 55 conveniently interchangeable. The mechanism is compact and comparatively inexpensive. The automatic application to the level of the article to be ground by means of the ball and socket joint and its special construction, is an important advantage. 60 What we claim as new, and of our invention and desire to secure by Letters Patent, is:—
  1. In a grinding and polishing machine, the combination of a series of grit holders, connected to a ring, a series of grit holders connected to an inner ring, an intermediate screw threaded ring whose thread engages a thread on the 65 interior of the first named or outer ring, and means for compelling the inner ring to rise and fall as this intermediate ring is raised or lowered relatively to the outer ring, the aforesaid mechanism provided with a central passage-way for the introduction of water centrally to the article

interior of the first named or outer ring, and means for compelling the inner ring to rise and fall as this intermediate ring is raised or lowered relatively to the outer ring, substantially as and for the purposes specified. 70

2. In a grinding and polishing machine, the combination of a series of grit holders connected to a ring, a series of grit holders connected to an inner ring, an intermediate screw threaded ring whose thread engages a thread on the interior of the first named or outer ring, and a flat ring extending over the top of the intermediate ring, and secured to the top of the inner ring, substantially as and for the purposes specified. 75

3. In a grinding and polishing machine, the combination of a series of grit holders forming a disk, and a second series of grit holders forming a disk, the grit holders of one series located alternately between the grit holders of the other series, and means for elevating and lowering the one series relatively to the other, substantially as and for the purposes specified. 80

4. In a grinding and polishing machine, the combination of a series of grit holders connected to a ring, a series of grit holders connected to an inner ring, an intermediate screw threaded ring whose thread engages a thread on the interior of the first named or outer ring and means for causing the inner ring to rise and fall as this intermediate ring is raised or lowered relatively to the outer ring, and a ball and socket joint, connected to the inner ring of the series of grit holders, substantially as and for the purposes specified. 85

5. In a grinding and polishing machine, the combination of a series of grit holders forming a disk, and a second series of grit holders forming a disk, the grit holders of one series located alternately between the grit holders of the other series, means for elevating and depressing the one series relatively to the other, and a ball and socket joint, 90 substantially as and for the purposes specified. 95

6. In a discal grinding and polishing machine, the combination of means for imparting a rotary motion to the disk, and a ball joint interposed between the disk and the means for imparting rotary motion to the disk, the ball of the joint having lugs, located in the plane of a diameter of the ball, and respectively extending into grooves in the socket, and a series of grit holders connected to a ring, a series of grit holders connected to an inner ring, an intermediate screw threaded ring whose thread engages a thread on the interior of the first named or outer ring, and a flat ring extending over the top of the intermediate ring, each series of grit holders arranged to receive between successive grit holders the respective grit holders of the other series, substantially as and for the purposes specified. 100

7. In a discal grinding and polishing machine, the combination of a socket secured to the disk, a ball received in this socket, a cap whereby the ball is kept in the socket, the lugs whereby a rotatory movement of the ball is communicated to the socket, these lugs being located in the plane of a diameter of the ball, a shaft connected to the ball, a conduit therein, and in the socket, and having its outlet at the grinding face of the disk, and a series of grit holders connected to a ring, a series of grit holders connected to an inner ring, an intermediate screw threaded ring whose thread engages a thread on the interior of the first named or outer ring, and a flat ring extending over the top of the intermediate ring and secured to the top of the inner ring, each series of grit holders arranged to receive between successive grit holders the respective grit holders of the other series, each series of grit holders extended out radially from their respective rings and increasing in size toward the peripheral line of the disk, which they go to form, substantially as and for the purposes specified. 110

8. In a grinding and polishing machine, the combination of a series of grit holders, connected to a ring, a series of grit holders connected to an inner ring, an intermediate screw threaded ring whose thread engages a thread on the interior of the first named or outer ring, and means for compelling the inner ring to rise and fall as this intermediate ring is raised or lowered relatively to the outer ring, the aforesaid mechanism provided with a central passage-way for the introduction of water centrally to the article 115

120

125

130

135

to be ground, substantially as and for the purposes specified.

9. In a discal grinding and polishing machine, the combination of a socket secured to the disk, a ball received in this socket, a cap whereby the ball is kept in the socket, the lugs whereby a rotatory movement of the ball is communicated to the socket, these lugs being located in the plane of a diameter of the ball, a shaft connected to the ball, a conduit therein, and in the socket, and having its outlet at the grinding face of the disk, and a series of grit holders connected to a ring, a series of grit holders connected to an inner ring, an intermediate screw threaded ring whose thread engages a thread on the interior of the first named or outer ring, and a flat ring extending over the top of the intermediate ring and secured to the top of the inner ring, each series of grit holders arranged to re-

ceive between successive grit holders the respective grit holders of the other series, each series of grit holders extended out radially from their respective rings and increasing in size toward the peripheral line of the disk, which they go to form, the said shaft being provided with the passage M and a passage M^2 , M^3 , M^4 , provided through the ball, socket and rings for the conduct of water therethrough, substantially as and for the purposes specified.
